UNITED STATES PATENT OFFICE.

EDMUND A. SCHWARTING AND AUGUST R. SCHRADE, OF WACO, TEXAS.

LOOSE-LEAF BINDER.

Application filed February 23, 1924. Serial No. 694,704.

To all whom it may concern:

Be it known that we, EDMUND A. SCHWARTING and AUGUST R. SCHRADE, citizens of the United States, residing at 5 Waco, in the county of McLennan and State of Texas, have invented certain new and useful Improvements in Loose-Leaf Binders, of which the following is a specification, reference being had to the accompanying drawings.

This invention relates to loose-leaf binders and has for its object the provision of a novel binder for holding ledger or other sheets in book formation to facilitate handling and filing thereof.

An important object is the provision of a loose-leaf binder which is equally well adapted to hold a large or small number of sheets or leaves, means being provided for effectually holding the base and top or covers, as they may be called, in firm clamping relation to the sheets which constitute the filler.

Still another object is the provision of a 25 binder which is particularly well adapted for use in connection with our posting device forming the subject-matter of application for patent filed Feb. 23, 1924, Serial No. 694,703 though the present device is complete in itself without reference to any specific posting device.

An additional object is the provision of a binder of this character which will be simple and inexpensive to manufacture, easy to operate, efficient and durable in service, and a general improvement in the art.

With the above and other objects and advantages in view, the invention consists in the combination and arrangement of parts 40 to be hereinafter more fully described and claimed and illustrated in the accompanying drawings, in which:

Figure 1 is a perspective view of a binder embodying our invention, parts being broken away and in section.

Figure 2 is a detail plan view of the operating mechanism.

Figure 3 is a detail section on the line 3—3 of Figure 1.

Figure 4 is a section showing a modification.

Referring more particularly to the drawings, the numeral 10 designates the base as a whole, which includes a relatively stationary section 11 and a hinged or movable section 12. The hinge structure is not illus-

trated as it forms no part of the present invention and for the further reason that it is well-known in the art and might be varied within considerable limits. This base 60 is intended to support a plurality of superposed leaves or sheets 13 which, as is well-known, are formed with holes 14. At spaced points the stationary section 11 of the base has plates 15 embedded or otherwise anchored therein, and slidably engaged through these plates are posts 16 which are provided at their lower ends with enlarged heads 17 preventing them from being withdrawn upwardly out of association with the 70 base. The plates 15 are counter-sunk or recessed for the reception of the heads 17 so that the bottom surface will be flush and will not cause scarring or marring of a table, stand or shelf upon which the binder 75 may be laid. These posts have rounded and tapered upper ends 18 and are formed with a plurality of grooves 19 for a purpose to be described. The sheets 13 have the holes 14 therein engaged upon these posts and in 80 this way all the sheets will be held against relative displacement.

The binding means comprises a top or cover 20 which includes a stationary section 21 and a movable section 22 hinged upon 85 one edge thereof and in the same manner that the section 12 is hinged upon the section 11. The member 21 is partially or entirely hollow, and fitting therewithin is a frame 23 within which are pivoted, at 24, 90 latches 25 which have their active ends engageable within the grooves 19 for holding the leaves 13 compressed. Extending through the hollow member 21 are bars 26 and 27 terminating in yokes 28 and 29, respectively, which straddle the latches 25 and which are pivotally connected therewith, as shown at 30. The inner ends of bars or rods 26 and 27 are threaded and connected by a turn-buckle 31 whereby the rods may 100 be adjusted so that the latches 25 may be disengaged simultaneously. Connected with the yoke 29 is a coil spring 32 which operates to hold the latches normally in engagement with the grooved posts. 105

For shifting the yokes to disengage the latches from the posts we provide a filler block 32^a which extends across the arms of the yoke 29 and with which is connected a plunger 33 slidable through a partition 34 110 in the member 21 and carrying a head or button 35.

7 In the use of the device the ledger sheets to be bound are engaged upon the posts and the top member is likewise slipped thereon, the posts passing through the holes provided in the top member 21. As the top is 5 pressed down the latches 25 will slide over the grooves in the posts until the sheets have been compressed fully or to the desired extent and the latches will remain engaged with the grooves and exert a pawl and ratchet-like action which will prevent the cover or top from moving upwardly. When, for any reason, it is desired to remove the top, as for instance when inserting 10 more sheets or in removing the same, it is merely necessary that the operator grasp and pull upon the head or button 35 which will result in moving the yokes and rods longitudinally against the action of the 15 spring 32 so that the latches will be withdrawn from engagement with the posts.

In the form of the device above described, the posts are removable from the base. In 20 Figure 4 we have illustrated a modification 25 in which the posts are formed with longitudinal grooves 16^a within which engage the ends of screws 15^a engaged within threaded bores in the plates 15. In this instance the posts are not removable from the base unless the screws 15^a be retracted, these screws 30 normally acting to permit the posts to slip through the plates until the ends of the grooves engage the screws. This form is especially well adapted for use in connection 35 with the posting device forming the subject-matter of the above referred to co-pending application.

From the foregoing description and a 40 study of the drawings it will be apparent that we have thus provided a simply constructed, inexpensive and very efficient binder which will be convenient to use and which will save time, labor and annoyance in binding ledger or other sheets. Owing 45 to the simplicity of the construction and the fewness of the parts, it is evident that there is very little to get out of order so that the device should have a long life and satisfactorily perform all of its functions.

50 While we have shown and described the preferred embodiment of our invention, it is of course to be understood that we reserve the right to make such changes in the form, construction and arrangement of parts as 55 will not depart from the spirit of the invention or the scope of the subjoined claims.

Having thus described our invention, what we claim as new and desire to secure by Letters-Patent, is:

60 1. In a binder, a base, posts rising from and pivotally mounted through the base, a top formed with holes for the passage of the posts, a pair of members movable longitudinally within the top, latches pivoted 65 within the top and pivotally connected with

said members for cooperation with the posts for holding them, means connected with the members normally urging the latches into operative position, and means for moving said members to release the latches. 70

2. In a binder, a base, posts rising therefrom formed with grooves, a top having holes for the passage of the posts, a pair of members longitudinally movably mounted within the top, latches pivoted within the 75 top cooperating with said posts and pivotally connected with said members, spring means urging the members in one direction for throwing the latches into operative engagement with the posts, means for moving the members in the other direction to release the posts, and an adjustable element connecting said member. 80

3. In a binder, a base, posts rising therefrom formed with grooves, a top having 85 holes for the passage of the posts, a pair of members longitudinally movably mounted within the top, latches pivoted within the top cooperating with said posts and pivotally connected with said members, spring 90 means urging the members in one direction for throwing the latches into operative engagement with the posts, means for moving the members in the other direction to release the posts, and an adjustable element connecting said members consisting of a turnbuckle swivelly connected with one member and threadedly connected with the other. 95

4. A device of the character described comprising a base, posts rising therefrom 100 formed with peripheral grooves, a top formed with holes for the passage of posts, a pair of adjustably connected rods movable longitudinally within the top and terminating in yokes, latches pivoted within the top cooperating with said posts and pivotally connected with the yokes, a spring urging the rods in one direction for normally holding the latches in engagement with the posts, and means for moving the rods in the 105 other direction. 110

5. In a binder, a base, posts rising from the base, a top having a hollow portion 115 formed with holes for the passage of the posts, a pair of longitudinally movable members located within said hollow portion, latches carried by said members and normally engaging the posts, and a rod connected with one member and terminating in an operating head, said hollow portion having a recess within which said head is normally disposed. 120

6. In a device of the character described, a base formed of hingedly connected sections, removable posts carried by one section, a top formed of similarly hingedly connected sections, one being formed with holes for the passage of the posts, the latter section of the top being formed hollow, a frame within the hollow section, latches piv- 125 130

oted within the frame and cooperating with the posts, means for releasing said latches, the posts being slidable through the base, and means for preventing disassociation of the posts from the base.

7. In a binder, a base, a pair of posts rising therefrom, a top having a hollow portion formed with holes for the passage of the posts, a pair of rods longitudinally movably mounted within said hollow portion and terminating in yokes, latches pivoted within the hollow portion and pivoted within the yokes for cooperative engagement with the posts, a rod connected with one of said first-named rods and slidable through one end of the hollow portion, an operating button on the second-named rod, and an adjustable element connecting the first-named rods whereby longitudinal movement of the first-named rods may be caused to effect simultaneous release of the latches.

8. In a device of the character described, a base, a pair of posts extending therethrough and rising therefrom, a top having a hollow portion formed with holes for the passage of the posts, the posts being peripherally grooved, a pair of rods longitudinally movably mounted within said hollow portion and terminating in forked

yokes, latches connected with and within said yokes for operative engagement with the posts, a handle member connected with one yoke, and spring means holding both yokes normally with the latches engaging the posts.

9. In a device of the character described, a base, a pair of posts extending therethrough and rising therefrom, a top having a hollow portion formed with holes for the passage of the posts, the posts being peripherally grooved, a pair of rods longitudinally movably mounted within said hollow portion and terminating in forked yokes, latches connected with and within said yokes for cooperative engagement with the posts, a handle member connected with one yoke, spring means holding both yokes normally with the latches engaging the posts, the adjacent ends of the rods being threaded oppositely, and a turn-buckle connecting the threaded ends of the rods for effecting adjustment thereof to insure simultaneous action of the latches.

In testimony whereof we hereunto affix our signatures.

EDMUND A. SCHWARTING.
AUGUST R. SCHRADE.
